ADJUSTABLE RECOIL GUN PAD

Filed April 14, 1931

W. J. Morgan
INVENTOR.

BY C. A. Harpman
ATTORNEY.

UNITED STATES PATENT OFFICE

WILLIAM J. MORGAN, OF YOUNGSTOWN, OHIO

ADJUSTABLE RECOIL GUN PAD

Application filed April 14, 1931. Serial No. 529,927.

This invention relates to gun pads.

The principal object of this invention is to provide a gun pad that will take up the recoil and one which provides for adjustment.

5 A further object of the invention is to provide adjustments for the gun pad which will change the "drop" of the gun.

A still further object of the invention is to provide adjusting means which will change 10 the "pitch" of a gun by adjustments.

With the foregoing and other objects in view which will appear as the description proceeds, the invention resides in the combination and arrangement of parts and in the 15 details of construction hereinafter described and claimed, it being understood that changes in the precise embodiment of the invention herein disclosed, can be made within the scope of what is claimed, without departing from 20 the spirit of the invention.

The invention is illustrated in the accompanying drawings, wherein:—

Figure 1 is a side elevation of the device, 25 with parts broken away, mounted upon a gun stock.

Figure 2 is a side elevation of the device mounted upon a gun.

Figure 3 is a side elevation of the device 30 mounted upon a gun and shown in an adjusted position.

Figure 4 is a cross section taken on line 4—4 of Figure 1.

Figure 5 is a cross section taken on line 35 5—5 of Figure 1.

Figure 6 is a detail perspective view showing a modification of a recoil or spring part.

By referring to the drawings it will be 40 seen that there is provided a plate member 1 which is secured to a gun stock 2 by means of screws 3. This plate member 1 is pro-

vided with a central slot 4. Functioning in 45 this central slot 4 there is provided an adjustment bolt 5 with a head 6 slidably main-

tained in a recess 7 of the plate member 1. The plate member 1 is provided with a 50 notched surface 8 which functions with a plate 9 which has a notched surface 10 function-

ness. It will also be seen by referring to Figure 1 that the plate 9 is provided with a recessed area 11 formed on a surface opposite to that of the notched surface 10 of the plate 9. It will also be seen that the plate 9 is provided with threaded openings 12 for the reception of a pair of threaded lugs 13. These threaded lugs 13 pass through an elastic cushion member 14 and into a shoulder portion 15 of the device. This shoulder portion 15 is held in adjustable relation by means of adjustable threaded caps 16 which function upon the threaded lugs 13. Each of these adjustable threaded caps 16 is provided with a shoulder 17 which functions against a seat 18 in openings 19 of the shoulder portion 15. The adjustable threaded caps 16 not only are used to place tension upon the elastic cushioning member 14 but also to change the "pitch" of the gun by turning down one of the adjustable threaded caps 16 farther than the other in order to give a desired angle to the shoulder portion 15 in relation to the gun stock 2 and connecting parts. By referring to Figure 3 it will be seen that the device is shown in an adjusted position in order to change the "drop" of a gun 20. This is accomplished by loosening a central threaded cap 21 which functions upon the adjustment bolt 5. This central threaded cap 21 is turned out sufficiently to allow the notched surfaces 8 and 10 to disengage in order to allow for desirable adjustment. When this adjustment has been made the central threaded cap 21 is turned down securing the device 75 in a desired position. It will be seen that the shoulder portion 15 is provided with a recessed area 22 for the reception of the elastic cushion member 14 when held under tension. By referring to Figures 1 and 4 it will be 80 seen that the recessed areas 11 and 22 have boundary areas 23 in order to provide means for a more delicate adjustment of the elastic cushion member 14 in taking care of recoil of gun when being fired. If the recoil 85 is to be given a maximum recoil range the elastic cushion member 14 is not held under tension sufficient to force the parts of the same into the recessed areas 11 and 22. In that case these recessed areas 11 and 22 act 90

50 made of metal of suitable strength and light-

as air cushion compartments to help in absorbing the recoil in the gun 20 when fired.

By referring to Figure 1 it will be seen that the shoulder portion 15 is provided with an upper extended curved portion 24 in order to more perfectly fit the shoulder portion 15 to the shoulder of a person firing the gun 20.

By referring to Figure 6 it will be seen that there is provided a modified recoil member 25 which is made of spring metal with a central opening 26 for the reception of the adjustment bolt 5 and has each end 27 bifurcated in order to function with the threaded lugs 13.

It is understood that in order to fit the device to gun stocks the plate member 1 may be formed, if desired, with a tapered circumferential portion extending from a contact point 28 to the notched surface 8. If this form is used it is obvious that the fitting of the device to an ordinary gun stock 2 may be done more easily.

What I claim is:—

1. In a device of the class described, a plate member secured to a gun stock, a central slot in said plate member, a recessed portion formed about said central slot, an adjustment bolt functioning in said recessed portion and slot, a notched surface formed on said plate member, a plate with notches functioning with said plate member, two oppositely disposed threaded openings in said plate, a pair of lugs functioning in said oppositely disposed threaded openings, a shoulder portion, an elastic cushion member functioning between said shoulder portion and said plate, means for holding said shoulder portion in adjustable relation to said plate, substantially as described.

2. In a device of the class described, a plate member secured to a gun stock, a central slot in said plate member, a recessed portion formed about said central slot, an adjustment bolt functioning in said recessed portion and slot, a notched surface formed on said plate member, a plate with notches functioning with said plate member, two oppositely disposed threaded openings in said plate, a pair of lugs functioning in said oppositely disposed threaded openings, a shoulder portion, spring cushion means functioning between said shoulder portion and said plate, means for holding said shoulder portion in adjustable relation to said plate, substantially as described.

3. In a device of the class described, a plate member secured to a stock of a gun, said plate member provided with a notched surface, a second plate member functioning with said plate member and having a notched surface, means for adjusting said plates in relation to each other in order that said notched surfaces may be held in fixed relation to each other, a shoulder portion held in

adjusted relation to said second plate member, an elastic cushion member secured between said shoulder portion and said second plate member, substantially as described for the purpose set forth.

4. In a device of the class described, a plate member secured to a gun stock, a central slot in said plate member, a recessed portion formed about said central slot, an adjustment bolt functioning in said recessed portion and slot, a notched surface formed on said plate member, a plate with notches functioning with said plate member, two oppositely disposed threaded openings in said plate, a pair of lugs functioning in said oppositely disposed threaded openings, a shoulder portion, an elastic cushion member functioning between said shoulder portion and said plate, means for holding said shoulder portion in adjustable relation to said plate, an upper extended curved portion on said shoulder portion, substantially as described.

In testimony whereof, I affix my signature.

WILLIAM J. MORGAN.
